UNITED STATES PATENT OFFICE

FREDERICO NAPOLI BENDELARI, OF JOPLIN, MISSOURI

ORE JIG

Application filed July 11, 1927. Serial No. 204,843.

This invention relates to ore separating or concentrating apparatus and more particularly to pulsating ore jigs.

The principal object of this invention is to provide a compact and relatively inexpensive ore jig which is rapid and efficient in its operation.

Another object of this invention is to provide a pulsating ore jig wherein the pulsations of water through the ore bed are produced by means of a reciprocating diaphragm or flexible plunger arranged beneath the ore grate.

A further object of this invention is to provide a pulsating ore jig wherein the ore to be separated is subjected to short rapid pulsations of water by means of a reciprocating flexible diaphragm arranged directly beneath the ore grate.

20 A further object of this invention is to provide a pulsating ore jig wherein the pulsion effect of the plunger on the bed of ore to be separated is greater than the suction effect whereby a more complete and rapid separation of the ore is effected.

Other objects and advantages of the invention will become apparent from the course of the following description.

In the accompanying drawings I have shown a preferred embodiment of my invention. In this showing:

Figure 1 is a side view,

Figure 2 is a vertical section taken on line 2—2 of Figure 1,

Figure 3 is a section taken on line 3—3 of Figure 2, and,

Figure 4 is a detail view of the chatter.

Referring to the accompanying drawings reference numeral 10 indicates a plurality of upright supports preferably steel L-beams to which are secured in any suitable manner walls 11 preferably formed of sheet metal to form a hopper 12. The lower wall or plate 13 is inclined as shown in Figure 2 to form a hutch 12'. In the upper portion of the hopper 12 is arranged a grate 14 on which is arranged a sieve or screen 15 of any desired mesh. A cell 16 is provided above the grate 14 and the sieve or screen 15 and is open on one side thereof to discharge material upon

the spout 17. A tail board 18 extending longitudinally of the discharge opening in the cell 16 is arranged between the interior of the cell and the spout 17. A chatter 18' is arranged adjacent the tail board 18 and extends longitudinally of the cell 16 and through one side wall thereof and communicates with any suitable discharge spout (not shown). The chatter 18' preferably consists of a pipe provided with a plurality of alined spaced openings 19'.

A diaphragm support 19 is arranged in the lower portion of the hopper 12 and is provided with a plurality of openings 20 communicating with the hutch 12'. A flexible diaphragm 21 substantially spherical in shape and preferably formed of rubber of a suitable thickness is secured to the diaphragm support 19 by means of an annular ring 22 arranged above the edge of the diaphragm 21 and secured to the support 19 in any suitable manner as by means of nuts and bolts 23. The diaphragm 21 is secured to a reciprocating plunger rod 24 by means of a pair of disks 25 arranged above and below the diaphragm 21 and secured together by means of nuts and bolts 26. A threaded restricted portion 27 of the plunger 24 is received in openings in the disks or plates 25 and in the diaphragm 21 and the disks are secured in position 28 against a collar 28 on the plunger 24 by means of a nut 29.

The plunger rod 24 passes through a cylindrical pipe 30 secured to the diaphragm support 19 and the lower inclined plate 13 of the hutch 12' and is detachably secured to the eccentric strap 31 carried by the eccentric 32 mounted on the shaft 33. The shaft 33 is suitably mounted in journals 33' carried by cross beams 34 secured to the uprights 10. A driving pulley 35 is secured to one end of the shaft 33 and a balance or fly wheel 36 is secured to the other end of such shaft.

Water is supplied to the hopper 12 from the pipe 37 provided with a check valve 38. A discharge spout 39 is arranged in the lower portion of the hutch 12' and is provided with a control gate 40.

The operation of the apparatus is as follows:

The ore to be treated is introduced into the cell 16 and a suitable amount of water is introduced into the hopper 12 and the hutch 12' from the pipe 37. The pulley 35 is rotated from any suitable source of power (not shown) and a reciprocating movement is imparted to the plunger rod 24 by means of the eccentric 32 and the strap 31. This reciprocating movement of the plunger 24 imparted to the diaphragm 21, causes the water in the hopper 12 to pulsate through the grate 14, the sieve or screen 15 and the bed of ore arranged thereon. The shaft 33 is designed to rotate at a relatively high speed in order to give rapid pulsations to the body of water in the hopper 12. Moreover, the eccentric 32 is designed to impart a relatively short stroke to the plunger rod 24, it having been discovered that the ore is more effectively separated from the waste material in the cell 16 by short rapid pulsations. In order that the pulsion stroke of the diaphragm 21 may have a much greater effect on the bed of ore than the downward or suction stroke of the diaphragm, the check valve 38 is designed to close on the upward or pulsion stroke owing to the increased pressure of the water in the hopper 12 produced by such upward stroke, and to open on the downward or suction stroke thereby admitting water freely during the last named stroke. In this manner the material on the sieve or screen 15 is forced sharply upward on the pulsion stroke of the diaphragm 21 but settles more gradually during the downward stroke of the diaphragm.

The finely divided ore passes through the sieve or screen 15 into the hopper 12 and thence through the openings 20 into the hutch 12'. The fine ore in the hutch may be drawn off as desired through the spout 39. The larger particles of ore and chats stratify into layers on the sieve or screen 15 during the separating operation and are retained thereon by means of the tail board 18. The lighter chats or waste materials are carried over the chatter 18' with the discharge water onto the spout 17. The richer chats are drawn off by the chatter 18'.

It will be readily apparent that by providing a flexible diaphragm directly beneath the ore grate that the separate plunger compartments commonly employed in the type of jigs heretofore employed are dispensed with thereby making the jig more compact and less cumbersome. Moreover, by making the jig of sheet metal the device is lighter and more readily assembled than the jigs heretofore used.

While I have shown and described a jig consisting of a single cell or unit it will be readily apparent that the jig may be formed of a plurality of cells or units by mechanically connecting the separate units together and

operating them from a single source of power.

While I have described in detail the preferred embodiment of my invention it is to be understood that various changes in the size, shape and arrangement of parts may be resorted to without departing from the spirit of the invention or the scope of the subjoined claims.

I claim:

1. In a jig of the character described, a tank adapted to contain liquid and divided by a stationary partition into a compartment above said partition and a closed chamber below said partition, said partition having an opening therein, an imperforate plunger of flexible material attached to said partition around said opening, there being passages in the partition disposed around the flexible plunger, said passages being adapted to deliver to said closed chamber, means connected to said flexible plunger through said opening for operating said plunger, and means for withdrawing material from said closed chamber.

2. In a jig of the character described, a tank adapted to contain liquid and divided by a stationary partition into a compartment above said partition and a closed chamber below said partition, said closed chamber having a central tubular opening therethrough communicating at its upper end with said compartment and at its lower end with a space below said chamber, an imperforate plunger of flexible material attached to said partition around the upper end of said opening, said partition being provided with passages disposed around the flexible plunger and adapted to deliver to said closed chamber, means connected to said flexible plunger through said tubular opening for operating said plunger, and means for withdrawing material from said closed chamber.

In testimony whereof I affix my signature.

FREDERICO NAPOLI BENDELARI.
